DECORATIVE GRILLE PANEL FOR A SPEAKER CABINET OR THE LIKE

Gordon L. Duern, Waterloo, Ontario, Canada, assignor to Dominion Electrohome Industries Limited, Kitchener, Ontario, Canada

Filed Sept. 12, 1962, Ser. No. 71,707

Term of patent 14 years

(Cl. D26—14)

FIG. 1

FIG. 2

FIGURE 1 is a front perspective view of a decorative grille panel for a speaker cabinet or the like, showing my new design; and

FIGURE 2 is an enlarged fragmentary perspective view thereof.

The design is characterized by upper and lower sets of slats with the slats in the upper layer being spaced apart from each other a distance equal to the width of a slat and the slats in the lower layer similarly being spaced apart from each other a distance equal to the width of a slat, the slats intersecting to define square openings with semi-circular cutout portions provided at the center of each side of the square openings, the semi-circular cutout portions being on intersecting center lines, said center lines bisecting said semi-circular cutout portions and being at 45° to the horizontal all as shown.

I claim:

The ornamental design for a decorative grille panel for a speaker cabinet or the like, as shown and described.
